UNITED STATES PATENT OFFICE.

CHARLES F. HUGHES, OF VANCOUVER, BRITISH COLUMBIA, CANADA.

AUTOMATIC FIREARM.

1,190,653.

Specification of Letters Patent.

Patented July 11, 1916.

Application filed April 12, 1916. Serial No. 90,699.

To all whom it may concern:

Be it known that I, CHARLES F. HUGHES, a citizen of the Dominion of Canada, residing at Vancouver, British Columbia, Canada, have invented certain new and useful Improvements in Automatic Firearms, of which the following is a specification.

This invention relates to an improvement in a self-loading firearm of that class where- 10 in the recoil on the breech bolt of the shot fired is utilized to eject the empty shell, cock the hammer and compress the spring by which the breech bolt is returned with a fresh cartridge to the firing position. In 15 firearms of this class, as at present used, although the recoil reloads the rifle, the hammer is released to fire the shot by pressure of the finger on the trigger and while for ordinary use, this is a desirable condition, emergencies may arise wherein the 20 firearm may be required to fire as well as to load automatically.

The improvement as set forth in the following specification is designed to afford a 25 dual control of the hammer whereby it may be released by momentary pressure on the trigger, or automatically by return of the breech bolt to the firing position, if the trigger release is sustained.

30 The means by which this result is attained is fully set forth in the following specification, reference being made to the drawings by which it is accompanied, in which:

35 Figure 1 is a part section of a self-loading rifle, such as the Winchester, showing the hammer control in elevation. Figs. 2 and 3 are details in perspective of the trigger and supplementary sear, respectively, 40 and Fig. 4 is a section on the line 4—4, with the hammer removed.

In these drawings 2 represents the breech bolt which contains the firing pin, and 3 the side members of the same which extend for- 45 wardly for connection to the recoil spring as shown, which side members are endwise movable on the side edges 9 of the trigger guard member 8; 4 is the breech of the barrel, chambered to receive the cartridge, and 50 5 is a portion of the receiver or casing secured to the barrel, within which casing the breech bolt 2 is endwise movable. 6 is the

hammer which is pivotally mounted on its pin 7 in the trigger guard member 8. The trigger is represented by 10 and the pin on 55 which it is mounted by 11. The forwardly projecting end 12 of the trigger 10 engages, as at present, the sear notch of the hammer 6 to retain it in the cocked position, the hammer being automatically cocked by the 60 backward movement of the breech bolt 2 under the action of the recoil. Independently mounted on the trigger pin 11 is a supplementary automatic sear lever which passes under the pin 7 of the hammer and 65 alongside the lower part of it and the free end of this lever is upwardly and laterally offset, as at 13, to project, under the action of a spring 14, above the upper edge 9 of the lock guard 8 and into a groove 15 pro- 70 vided for it along the inner under edge of the side 3 of the breech bolt so that this end 13 will be engaged and depressed by the side 3 of the breech bolt at the termination 75 of its groove 15 when the breech bolt at- tains its firing position, as shown in the full lines of the drawing. On the inner side of this sear lever 13 is a projection 17, the forward edge of which coincides with the forward edge of 12, so as to similarly en- 80 gage the sear notch of the hammer 6. The hammer may thus be retained in the cocked position by the end 12 of the trigger sear and by the projection 17 of the automatic sear, and each retaining means is independ- 85 ently operable to retain or release the ham- mer. The automatic sear is pressed down to free its projection 17 from engagement with the sear notch of the hammer only 90 when the breech bolt is in the firing position, while the trigger engagement is retained unless the trigger is pressed to free it. Thus, if the trigger is pulled to release its end 12 from engagement with the sear notch of the hammer 6 and the breech bolt is in 95 the firing position, that is, at the forward limit of its movement, the hammer will fall to fire the shot, and if pressure is maintained on the trigger to hold its end 12 out of en- gagement with the sear notch of the ham- 100 mer, the recoil of the bolt 2 will throw back the hammer to the cocked position where it will be retained by the supplementary sear until the bolt is returned to the firing posi-

tion by its recoil spring, but when that position is attained the supplementary sear 13 will be pressed down by engagement of the end 16 of the groove 15 and the hammer will again be released and this automatic cocking and release will continue until the last cartridge from the magazine is fired, or until pressure on the trigger is released when the hammer will be retained in the cocked position by the trigger projection 12, even when the automatic sear is depressed from such engagement by the breech bolt. If it is required to fire a single shot the trigger must be pressed and immediately released. The mechanism will then act as a self-loading and cocking firearm.

I do not desire to be confined to the particular construction of the trigger and supplementary sear as set forth in the specification and drawing herewith, as such may be varied to meet the requirements of the various arms; but claim as my invention the combination of a direct control of the hammer by the trigger and by a supplementary sear released by movement of the breech bolt to the firing position.

Having now particularly described my invention, I hereby declare that what I claim as new and desire to be protected in by Letters Patent, is:

1. In a firearm, the combination with a breech bolt endwise movable under the recoil of the shot fired and a hammer adapted to be moved to the cocked position by the backward movement of the breech bolt, of means directly operable with the trigger for retaining the hammer in the cocked position, and means independent of the trigger for retaining the hammer in the cocked position, said means releasable by the breech bolt when that bolt is in its firing position.

2. In a firearm, the combination with a breech bolt endwise movable under the recoil of the shot fired and a hammer adapted to be moved to the cocked position by the backward movement of the breech bolt, of means directly operable with the trigger for retaining the hammer in the cocked position, a supplementary sear lever pivotally mounted to move independently of the trigger and adapted to engage the sear notch of the hammer and retain it in the cocked position, said lever adapted to be engaged by a part of the breech bolt when the same is in the firing position and release the supplementary sear from engagement with the sear notch of the hammer.

3. In a firearm, the combination with a breech bolt endwise movable under the recoil of the shot fired and a hammer adapted to be moved to the cocked position by the backward movement of the breech bolt, of means directly operable with the trigger

for retaining the hammer in the cocked position, a supplementary sear lever pivotally mounted on the trigger pin to move independently of the trigger, said sear lever having provision to engage the sear notch of the hammer to retain it in the cocked position, the free end of said lever being upturned and laterally offset to project in the path of a portion of the breech bolt and to be engaged and depressed by it to release the hammer at the forward limit of the movement of the bolt.

4. In a firearm, the combination with a breech bolt endwise movable under the recoil of the shot fired and a hammer adapted to be moved to the cocked position by the backward movement of the breech bolt, a trigger having an end forwardly projecting from the pin on which it is mounted and adapted to engage the sear notch of the hammer and retain the hammer in the cocked position, and a supplementary sear independently mounted on the trigger pin and adapted to engage the sear notch of the hammer when the same is in the cocked position, said supplementary sear being produced beyond this engaging shoulder and upwardly turned and laterally offset to project into a groove in the side of the breech bolt and adapted to be pressed down by the end of the groove to release the hammer when the bolt is at the forward limit of its movement.

5. In a firearm, the combination with a breech bolt endwise movable under the recoil of the shot fired and a hammer adapted to be moved to the cocked position by the backward movement of the breech bolt, of means for retaining the hammer in the cocked position, said means comprising a trigger having an end forwardly projecting from the trigger pin and adapted to engage the sear notch of the hammer, and a supplementary sear independently mounted on the same pin and adapted to engage the same sear notch of the hammer to retain it in the cocked position and provision for yieldingly projecting the end of the supplementary sear in the path of a portion of the breech bolt to be engaged and depressed from engagement with the sear notch of the hammer when the breech bolt is in the firing position.

6. In a fire arm, the combination with the endwise movable recoil operated breech bolt and a hammer adapted to be moved to the cocked position by the backward movement of said bolt, said bolt being provided with a groove and having a shoulder, said hammer having a single sear notch, a trigger, said trigger having a projecting end to engage in said sear notch of said hammer, a trigger pin on which said trigger is fulcrumed, and a sear lever mounted

at one end on said trigger pin and having its other end adapted to project into said breech bolt groove or be engaged by the shoulder of said breech bolt according to the position of the breech bolt, said sear lever having a projection to engage the sear notch of the hammer, all being arranged

when the trigger is pulled to release the hammer successive automatic firings of the fire arm are produced.

In testimony whereof I affix my signature.

CHARLES F. HUGHES.
